UNITED STATES PATENT OFFICE.

JOHN B. BAXTER, OF TROY, NEW YORK, ASSIGNOR TO COVERT MANUFACTURING COMPANY, OF WATERVLIET, NEW YORK, A CORPORATION OF NEW YORK.

COMBINED HARNESS SLIDE AND SNAP.

Application filed June 14, 1927. Serial No. 198,755.

This invention relates to improvements in combined harness slides and snaps of the kind having a slide for the breast connection, and an attaching snap pivotally connected to the slide and adapted to receive the eye of the neck yoke.

The object of the invention is to provide an improved combined harness slide and snap of the type referred to, of simple construction, 10 that will be strong, durable and efficient in use, that will operate easily, and that can be manufactured at low cost.

Important novel features of the invention reside in the special construction of slide and 15 attaching snap, the special mounting of the slide on the snap, and in the particular means for limiting the oscillatory movement of the slide relatively to the attaching snap.

The invention, with other objects and advantages thereof, and the particular construction, combination and arrangement of parts comprising the same, will be understood from the following detailed description, when considered in connection with the accompanying 25 drawings, forming part hereof and illustrating embodiments of the invention.

In the drawings:

Figure 1 is a side elevation of a combined slide and snap constructed in accordance with 30 the present invention.

Fig. 2 is a top plan view.

Fig. 3 is a section on the line 3—3 of Figure 2, part of the attaching snap being shown in side elevation.

Fig. 4 is a central transverse section of the slide.

Fig. 5 is a part section and part side elevation of a modified construction.

Fig. 6 is a section on the line 6—6 of Figure 40 5, part of the attaching snap being shown in plan.

Fig. 7 is a transverse section of the slide.

Referring to a detail description of the particular embodiment of the invention illustrated in the drawings Figures 1 to 4 inclusive, A designates the slide of the device and B the attaching snap.

The slide A comprises a body portion 1 curved or rounded longitudinally and also 50 curved transversely, and provided with longitudinal marginal flanges 2 at its under side, the structure being of channel like form to slidably receive within the same at its under side a harness breast chain connection or the like. The side flanges 2 are shown substan-

tially semi-circular shape and coextensive with the body portion 1, the same being of substantial height at the central part of the body portion 1 and gradually decreasing in height towards the ends thereof. The bottom 60 face 2 of the body portion 1 of the slide joins the inner side faces 4 of the marginal flanges 2 in a gradual curve 2, and the ends 5 of the body portion 1 merge in a gradual curve into the ends of the flanges 2, the ends of the body 65 portion 1 and the marginal edge portions of the flanges 2 being rounded. As will be understood this structure affords strength and is of such a character as to prevent binding or cramping, and to provide for free sliding engagement of the links of the breast chain with the slide A. The slide A is provided with a pair of spaced apertured lugs 6 projecting above its upper face 5 centrally of its ends at 70 opposite side marginal portions thereof to 75 form bearings above the bottom chain engaging surface 3, said projecting portions being provided with apertures 8. The attaching snap member B comprises a hook portion 9 and a shank 10. Connected with the rear end 80 of the shank 9 is a cross head or bar 11 and extending rearwardly from said cross bar are spaced side arms 12. The side arms 12 near their rear end portions have enlarged rounded 85 portions 13 provided with apertures 14.

The slide A is adapted to be positioned between the side arms 12 of the attaching snap B with its projecting portions 6 extending in alignment with the enlarged rounded portions 13 of the side arms 12, and the apertures 14 90 and 7 of these parts in register. The slide A is pivotally connected to the attaching snap B by a rivet or equivalent fastening member 16 extending through the aperture 7 of the projecting portions 6 and apertures 14 of the 95 enlarged portions 13 of the side arms 12 of the attaching snap, said rivet having end heads to engage the outer side faces of the arms 12. The apertured portions 6 of the slide A loosely engage the rivet 16 to freely 100 rock about the same, the end faces of the portions 6 constituting bearing faces cooperating with the inner faces of the enlarged portions 15 of the arms 12.

The means for limiting the oscillatory 105 movement of the slide A relatively to the attaching snap B comprises lugs or projecting portions on the slide A adapted to engage the side bars 12 of the attaching snap B and limit the oscillatory movement of the slide in either 110

direction. 17 designates the stop lugs or portions projecting from the outer side of the side walls or marginal flanges 2, said stop lugs or projecting portions being shown located near the end portions of the slide adjacent the edges of the segmental shaped flanges 2, each stop lug being provided with a straight flat edge face 18 disposed at the proper angle to abut against the upper side faces of the side arms 12. Preferably as shown in Figures 1 to 4 of the drawings, 2 pairs of said stop portions or lugs 17 are provided, each side flange having thereon a pair of such stop portions or lugs.

15 The modified construction illustrated in Figures 5 to 7 of the drawings is the same as that shown in Figures 1 to 4, hereinbefore described, except that in this instance, only a single pair of stop portions or lugs are provided on one of the side flanges of the slide, and instead of two spaced apertured lugs projecting above this upper face for pivotally connecting the slide to the attaching snap, the slide is provided with only a single projecting portion disposed centrally of its sides. 20 In these views, C designates the slide and B the attaching snap. 19 designates the stop lugs on the slide C and 20 the apertured portions projecting from the upper side of the slide centrally of its ends. 21 is the rivet or like fastening member extending through the aperture 22 of the portion 20 and apertures 23 of enlarged portions 24 on the side arms 13.

25 The improved combined snap and slide hereinbefore set forth is of a simple, practical, inexpensive nature that will be strong, durable and efficient in use. The particular construction and connection of the slide to

the attaching snap is of a character to insure ease of operation, and the special means provided for limiting the oscillatory movement of the slide relatively to the attaching snap is of a simple, efficient nature, advantageously arranged with relation to the other parts of the structure.

What I claim is:

1. In a device of the class described, the combination of a slide adapted to receive a chain or the like at its under side, an attaching snap having rearwardly extending spaced side arms, means pivotally connecting the slide intermediate its ends to and between the side arms of the snap, and laterally projecting stop lugs on the slide adapted to engage one of the side arms of the attaching snap to limit the oscillatory movement of the slide in either direction relatively to the attaching snap.

2. In a device of the class described, the combination of a slide adapted to receive a chain or the like at its under side, said slide comprising a curved plate portion with side flanges at its under side, an attaching snap having spaced side arms, means pivotally connecting the slide to and between the side arms of the attaching snap, and a pair of laterally projecting lugs on one of the side flanges of the slide at the outer side thereof adapted to engage the side arms of the attaching snap and limit the oscillatory movement of the slide in either direction relatively to the attaching snap.
